UNITED STATES PATENT OFFICE.

DAN J. SCOTT, OF LONG BEACH, CALIFORNIA.

COLLAPSIBLE DRILL PIPE.

Application filed May 15, 1924. Serial No. 713,544.

This invention relates to collapsible drill pipes for drilling wells.

An object of this invention is the provision of means for saving time in drilling a well.

Another object of this invention is the provision of apparatus which reduces the number of additions of pipe in a string of drill pipes when drilling a well.

10 A further object of this invention is the provision of a collapsible drill pipe which may be extended when the depth of the well requires additional lengths of drill pipe.

15 With the foregoing objects in view, together with such other objects and advantages as may subsequently appear, this invention consists in the construction and arrangement of parts hereinafter described and claimed and illustrated in the accompanying drawings, in which:

20 Figures 1 to 7 inclusive show longitudinal sections of a well and elevational views of strings of drill pipe in various positions, said strings of drill pipe embodying my novel collapsible drill pipe.

25 Figure 1 shows the drilling apparatus in operative position,

Fig. 2 shows the drilling apparatus further down than in Fig. 1, the kelly having 30 reached its lowermost working position in a rotary table,

Fig. 3 shows the drilling apparatus in raised position preparatory to extend a collapsible tube of my invention,

35 Fig. 4 shows the drilling apparatus in raised position after a collapsible tube of my invention has been extended from the lower end,

40 Fig. 5 is similar to Fig. 4 except that it shows the drilling apparatus lowered to a position near the rotary table to which it is convenient for locking the parts of my improved collapsible pipe after extension thereof,

45 Fig. 6 shows the drilling apparatus in operative position after partly extending the collapsible drill pipe,

Fig. 7 shows the drilling apparatus in position requiring further extension of the 50 drill pipe,

Fig. 8 is a longitudinal section of a collapsible drill pipe broken away,

Fig. 9 is a transverse section taken on the line 9—9 of Fig. 8,

55 Fig. 10 is a longitudinal section of the

collapsible tube shown in Fig. 1, partly broken away, and showing the tube extended through its lower portion,

Fig. 11 is a longitudinal section of the collapsible drill pipe shown in Figs. 8 and 9, 60 and shows the same fully extended,

Fig. 12 is a longitudinal section of a modification of my collapsible pipe, the same being broken away,

Fig. 13 is a fragmentary view of Fig. 12, 65 showing certain parts of Fig. 12 in positions assumed when the pipe is extended,

Fig. 14 is an elevational view of the lower portion of Fig. 13, and

Fig. 15 is a longitudinal section of another 70 modification of my invention.

Referring to the drawings for a more detailed description thereof, the collapsible pipe of my invention comprises an upper pipe section 17 and a lower pipe section 18 75 threadedly engaging each other at 20. A pin 21 is provided to prevent the two sections from being accidentally separated.

The upper section 17 has a taper 22, the periphery of which converges towards a 80 neck 23, the upper end 24 of which is enlarged and provided with a recess 25. Adjacent the recess 25, the enlarged portion 24 is internally threaded to receive a kelly 26. The upper section 17 is internally threaded 85 to engage a threaded upper end portion 27 of a tubular section 28 to form a joint 27a. The section 28 is formed integral with a pipe 29. The section 28 is formed with a shoulder 30 adjacent its upper end portion 27. A rubber packer 31 is set in and encircles the section 28 and a ring 32 threadedly engages the section 28 adjacent the shoulder 30 to hold the packer 31 in place. The section 28 is also 90 formed with a shoulder 33 below which a reduced section 34 is provided with external threads 35. The section 34, which is contiguous with the pipe 29, is provided with a recess 36, the boundary of which is threaded to engage a threaded lug 37 to form a joint 37a.

95 The lug 37 is formed integral with a tubular member 39 into which is set peripherally thereof a packer 40 in contact with the pipe 29. A ring 41 threadedly engages the member 39 to hold the packer 40 in place. 100 The member 39 comprises a reduced lower end portion 42 provided with threads 43. The pipe 29 is externally threaded at its lower end to engage internal threads formed 105 in the upper end portion of a pipe 44 and 110

forming a joint 45 which is secured by a pin 46. The pipe 44 passes through the lower pipe section 18, the bottom of which is provided with a peripherally threaded plate 48 threadedly engaging internal threads formed in the lower end portion of the section 18. The plate 48 is provided with an aperture through which the pipe 44 passes with a working fit.

10 A coiled compression spring 49, encircling the pipe 44, is held between the upper surface of the plate 48 and the lower surface of an apertured member 51, slideable in the section 18 and encircling the pipe 44 with a 15 working fit.

The member 51 has a hexagonal perimeter, as shown in Fig. 9, to prevent its turning relative to the correspondingly formed portion of the inner perimeter of the section 18 20 over which it may slide. The member 51 is provided with a tapered recess 52 to receive the threads 35 of the section 34 when the pipe is extended, and for that purpose the member 51 is internally threaded adjacent 25 the aperture 52.

A collar 53 is formed internally in the pipe 44 and against this collar the member 51 is normally pressed by the action of the coiled spring 49. A collar 55 is formed internally 30 in the pipe 44, against the lower surface of which a member 56 abuts. The member 56 is normally held in abutment against the collar 55 by a coiled compression spring 57, the lower end of which rests on a peripherally threaded plate 58 which engages internal threads in the lower end portion of 35 the pipe 44.

The internal perimeter of the pipe 44 is hexagonal between the upper surface of the 40 plate 58 and the lower surface of the collar 55 to receive with a working fit the member 56, the external perimeter of which is hexagonal. The member 56 is provided with a tapered aperture 60 adapted to engage the 45 threaded section 42 of the member 39 when the collapsible pipe is extended, and is therefore threaded adjacent the aperture 60 to receive the threads 43 of the member 42. A pipe 61 is formed integral with the member 50 42 and passes through the aperture 60 and through the coil 57. The pipe 61 also passes through the plate 58 and with a working fit. The lower end of the pipe 61 is a tapered 55 threaded portion 62 adapted to be connected to a drill pipe 63 shown in Figs. 1 to 7 inclusive.

When a string of drill pipe of a given length has reached the lowermost working 60 position, as shown in Fig. 2, it is pulled upwardly to the position shown in Fig. 3, and, with the string of pipe held by slips 65, the joint 37^a is broken, thus allowing the collapsible pipe to be extended, as shown in Fig. 4. The string of pipe is then let down 65 to a convenient height above the rotary table

66, as shown in Fig. 5. In this position the threads on the member 42 bear against the threads adjacent the aperture 60 in the slideable member 56 and push the latter downwardly against the action of the coiled compression spring 57 until the lower surface of the member 39 rests on the upper surface of the collar 60. By such arrangement the threads on the member 43 and the threads adjacent the aperture 60 are not liable to be 70 injured. The parts of the extended collapsible pipe may then be locked in position, preparatory to proceeding with the 75 drilling operation.

In order to lock the parts, the section 42 is threaded into the aperture 60 when the parts assume the position shown in Fig. 10. The string of drill pipe may then be let down into the well, as shown in Fig. 6. When the string of pipe of the length represented by Fig. 6 has reached its lowermost working position, as shown in Fig. 7, the string of drill pipe is then raised until the collapsible tube is above the rotary table 66. The joint 27^a is then broken and the collapsible pipe may be extended until the shoulder 33 of the member 28 rests on the collar 53, the lower threads of the section 34 coming into contact with the upper threads formed adjacent the recess 52 and 80 pressing the slideable member 51 downwardly against the action of the coiled compression spring 49. The section 34 is then threaded into the recess 51, and the parts are thus locked, after which the string of drill pipe 85 may be lowered into the well and the drilling 90 proceeding with.

In the modification shown in Figs. 12, 13 and 14, the collapsible drill pipe comprises an upper section 70 threaded at 71 to a lower section 72. The upper section 70 is provided at its upper end with internal flat-faced threads 73 to receive the threaded end of the kelly 26. The upper section 70 is provided with internal flat-faced threads 74 which engage external flat-faced threads 75 formed on a section 76 which is part of a body 77, having at its lower end a section 78 provided with external flat-faced threads 79. The body 77 is provided with a packer 80. A ring 81 threadedly engages the body 77 to keep the packer 80 in place. The lower end of the section 79 is contiguous with a pipe 83. The lower end of the pipe 83 threadedly engages a pipe 84. The lower end of the pipe 84 is provided with internal flat-faced threads 85 and the lower end of the section 72 of the collapsible pipe is provided with internal flat-faced threads 86.

The section 78 is recessed and provided 125 with internal flat-faced threads 87, which engage flat-faced threads 88 formed in a section 89 which forms part of a body 90 having at its lower end a section 91 provided with external flat-faced threads 92, 130

The body 90 is provided with a set-in packer 93 above which in engagement with the body 90 is a ring 94 to hold the packer 93 in place. A pipe 95 is contiguous with the section 91 and passes through the pipe 84.

In operating this collapsible tube to extend the same, the joint which the section 89 makes with the section 78, is broken and the pipe extended, and the threads 92 of the section 91 may be made to engage the threads 85 of the pipe 84. Subsequent extension of the device comprises breaking the joint which the section 76 makes with the upper part 70 of the device and then extending the device and causing the threads 79 of the section 78 to engage the threads 86 formed in the lower section 72 of the device. The threads 79 and 86 are preferably so formed that their engaging ends may be at right angles to each other when the pipe is extended, and for this purpose an arrow 96 is formed on the pipe 84 and an arrow 97 is formed on the pipe 95. The threads 79 and 86 are so formed that when the arrows 97 and 96 are in registration, the engaging ends of these threads will be at right angles to each other, as will also the engaging ends of the threads 92 and 85 when the tube is extended.

Fig. 15 illustrates still another modification of my invention, which modification comprises a pipe 99 comprising an upper section 100 threaded at 101 to a lower section 102. The pipe 99 connects with a pipe 103 which connects to a pipe 104. The pipe 99 is provided at its upper end with a tapered recess 105 to receive a kelly and threads adjacent the recess for locking this pipe to the kelly. A tapered recess 106 with threads adjacent this recess is formed in the pipe 99 to receive a threaded end 107 when the string of pipe is partly collapsed.

The pipe 103 also comprises a threaded tapered section 108 which may be screwed into a member 109 slidable in the pipe 99. A coiled compression spring 110 is positioned within the pipe 99, encircling the pipe 103 and is held below the lower surface of the member 109 and the upper surface of a plug 111 which threadedly engages the lower end of the pipe 99. The lower end of the pipe 103 comprises the tapered threaded section 106 which threadedly engages the upper end portion of the pipe 104 when the string of pipe comprising pipes 99, 103 and 104 is extended.

The pipe 103 also comprises a tapered threaded portion 113 at its lower end which may be fitted into a corresponding recess when the string of pipe is collapsed.

It will be readily seen that to collapse the pipe shown in Fig. 15, which is there shown in extended position, the member 108 may be unthreaded from the member 109 and the pipe 99 let down until the end 107 is adja-

cent the recess 106 after which the end 107 may be threaded into this recess. Similarly when the pipe 103 is to be positioned within the pipe 104, the section 106 is unthreaded from the upper end of the pipe 104 and subsequently the end section 113 is threaded into a corresponding recess.

This invention has been described but modifications thereof may be devised without departing from the spirit thereof, and it is to be understood that such modifications come within the scope of this invention.

What is claimed is:

1. A collapsible drill pipe for wells, comprising a plurality of concentric pipes adapted to be locked together in collapsed and extended positions, and slideable locking members resiliently supported in certain of said pipes.

2. A collapsible drill pipe comprising a plurality of concentric pipes adapted to be collapsed or extended, and means including threads for holding said pipe in collapsed or extended position.

3. A collapsible drill pipe including an outer pipe and an inner pipe, threads formed adjacent each end within said outer pipe, a head formed upon said inner pipe, and threads formed upon said head adapted to engage the threads at either end of said outer pipe, whereby said inner and outer pipes may be locked in collapsed or extended position.

4. A collapsible drill pipe including an outer pipe and an inner pipe, threads formed adjacent each end within said outer pipe, a head formed upon said inner pipe, threads formed upon said head adapted to engage the threads at either end of said outer pipe, whereby said inner and outer pipes may be locked in collapsed or extended position, and packing carried by said head adapted to bear against said outer pipe.

5. A collapsible drill pipe including an outer pipe having its lower end provided with a collar in which is formed an aperture, an inner pipe slidable within said aperture, threads formed upon said inner pipe, threads formed in the upper portion of said aperture adapted to be engaged by the threads upon said inner pipe, whereby said pipes may be locked together in extended position, and packing carried by said inner pipe bearing upon the interior surface of said outer pipe as and for the purpose described.

6. A collapsible drill pipe including an outer pipe, an inner pipe, a third pipe disposed within said inner pipe, means for locking said inner pipe within said outer pipe against rotation and against longitudinal movement within said outer pipe, means for locking said third pipe against rotation and against longitudinal movement within said inner pipe, and packing means for prevent-

ing fluid flow between said inner and outer pipes and between said inner and third pipes.

7. A collapsible drill pipe comprising an outer pipe and an inner pipe, a head formed upon said inner pipe, threads formed upon said head, threads formed upon the interior of said outer pipe engageable with the threads upon said head to lock said outer and inner pipes together in collapsed position, an inwardly extending flange formed

upon said outer pipe, a collar slidable within said outer pipe about said inner pipe, spring means for resiliently maintaining said collar against said flange, and threads 15 formed upon said collar adapted to engage with the threads upon said head so as to lock said inner and outer pipes in extended position.

In testimony whereof I have signed my 20 name to this specification.

DAN J. SCOTT.
